UNITED STATES PATENT OFFICE.

HUGH TODD, OF TORONTO, ONTARIO, CANADA.

DOOR AND GATE HANGER.

No. 902,348.

Specification of Letters Patent.

Patented Oct. 27, 1908.

Application filed May 15, 1908. Serial No. 433,112.

To all whom it may concern:

Be it known that I, HUGH TODD, of the city of Toronto, in the county of York, in the Province of Ontario, Canada, have invented certain new and useful Improvements in Door and Gate Hangers, of which the following is the specification.

My invention relates to improvements in door and gate hangers and the object of the invention is to devise a strong, durable and efficient hanger for a door or the like, which will always insure of the door moving evenly and without liability of jamming and in which the use of drags is entirely dispensed with.

A further object is to provide a ready means for adjusting the upright edge of the door, so that it will be in the vertical position when in working order, and also a ready means to adjust the door to the proper height above the floor.

To effect these ends I construct my invention in the manner which I shall presently describe in reference to the accompanying drawings.

Figure 1, is a perspective view of a sliding door hung on my improved hangers. Fig. 2, is a vertical section. Fig. 3, is a cross section of the door showing the means of attaching one set of the hangers thereto.

In the drawings like letters of reference indicate corresponding parts in each figure.

The hangers shown in the drawings are made, of course, on an exaggerated scale as compared with the door for the purpose of clearly illustrating the parts involved in my invention.

A is the door.

B is a bracket secured on the partition above the door.

C is a lever pivoted in a bracket.

E is a screw spindle provided with a forked upper end, which is pivotally connected to one end of the lever C. The lower end of the screw spindle extends freely through a bracket E' and is provided with nuts E² and E³ above and below the bracket by which the lever C may be adjusted.

F is a bar having a forked upper end pivotally connected to the end of the lever C.

G is a screw spindle having a forked end pivotally connected to the arm F. The screw spindle G extends through a bracket

G' and has nuts G² and G³ at each side of the bracket G', whereby the position of the arm F may be adjusted.

H is a reverse L-shaped arm pivotally connected at the top to the bottom of the arm F and at the bottom to an arm I, which is held on the end of the stub arbor J journaled in bearings J' attached to the door. The stub arbor J has a socket into which fits a stub arbor J² journaled in bearings J³ at the opposite side of the door and to which is connected an arm I', which is connected to a similar arm to the arm H at the opposite side of the door. I only use one arm H and its co-acting parts in doors or gates of light construction, but where the door is heavy I preferably use the parts referred to in duplicate, one on each side of the door.

K is a lever and K' is a bar connected to one end of the lever, such lever and arm being constructed and adjusted in the exact manner in which the lever C and bar F are constructed and adjusted.

L is a rod pivotally connected to the lower end of the arm K' at the top and at the bottom pivotally connected to the lower end of the arm M, which is secured on the arbor M' journaled in suitable bearings in the plates N and N' secured to the rear edge of the door A.

M² is a rod connecting the end of the arm M and rod L to the ends of the arms I and H, the connections being pivotal connections.

O is an arm secured in the end of the arbor O'.

P and P' are gear wheels secured on the ends of the arbors O' and M', such gears meshing with each other, so as to cause the arms O and M to move in unison.

O² is a rod pivotally connected to the upper end of the arm O and at the bottom end pivotally connected in the slot O³ in the bar O⁴. The bar O⁴ is as shown in the drawing particularly Fig. 2, at one side of the door and is supported to slide on tracks O⁵ forming part of the plate O⁶ located in the channel O⁷ (see Fig. 2).

O⁸ is an adjusting screw spindle, which extends through a hole in the bar O⁴ and is provided with a nut O⁹ by which the bar may be adjusted vertically on the tracks O⁵. The plate is provided with a slot 2 to allow of the longitudinal movement of the screw spindle

O⁸. To effect this adjustment I provide a screw spindle O¹⁰, which is pivotally connected at one end between lugs O¹¹ attached to the bar O⁴ and at the opposite end extends through a lug O¹² attached to the plate O⁶. Adjusting nuts O¹³ and O¹⁴ are provided at each side of the lug O¹². The top and bottom of the door are provided with guiding grooves A' and A² formed of T-shaped angle bars with the groove outermost.

3 is an upper plate having rollers 4 journaled in spindles 5 extending through the same, the rollers being separated by strips 6, the diameter of the rollers being of course wider than the width of the strips. The rollers run in the grooves A'.

7 is a bar secured to the sill and having a series of rollers 8 journaled on pins in the bar, such rollers being separated by strips 9 secured to the bar and of less width than the diameter of the rollers. The rollers 8 run in the grooves A². It will be seen by these guiding grooves and rollers that I provide against any lateral swing of the door during its backward and forward movement.

By adjusting the bar O⁴ and the levers C and K as hereinbefore described the door may be raised or lowered to any desired height in relation to the guiding rollers 4 and 8, so that it will move evenly in relation thereto and by adjusting the bars F and K' the set of the operating levers and bars may be altered so as to insure of the edge of the door being in the vertical position and thereby also insure the proper movement of the door and grooves thereof at the top and bottom in relation to the guiding rollers 4 and 8. In fact my door by the arrangement of levers and adjusting means hereinbefore described may be adjusted very quickly and accurately to suit the frame in which it is designed to slide no matter whether there be a subsidence of such frame or not.

The dotted position of the door shown in the drawing will give an exact idea of the change of position of the lever arms and rods when the door is thrown back. The frame H will, of course, be at right angles to the door opening as indicated by dotted lines in Fig. 1.

What I claim as my invention is:

1. In a door hanger, the combination with the door and suitable guide-ways therefor, of a stub shaft journaled in the door, an arm connected to the stub shaft, a reverse L-shaped arm connected to the lower end of the aforesaid arm at the bottom, an adjusting device secured to the head of the door frame and a pivotal connection between the adjusting device and the upper end of the L-shaped arm as and for the purpose specified.

2. In a door hanger, the combination with

the door and suitable guide-ways therefor, of a stub shaft journaled in the door, an arm connected to the stub shaft, a reverse L-shaped arm connected to the lower end of the aforesaid arm at the bottom, an adjusting device secured to the head of the door frame, a pivotal connection between the adjusting device and the upper end of the L-shaped arm, a double plate secured to the inner edge of the door, an arbor journaled in the plate, an arm on the arbor, a rod connecting such arm to the bottom of the arm on the stub shaft journaled in the door, a second rod pivotally connected to the lower end of the arm on the arbor and adjusting means secured to the head of the door frame and pivotally connected to the rod connected to the arms on the arbor as and for the purpose specified.

3. In a door hanger, the combination with the door and suitable guide-ways therefor, of a stub shaft journaled in the door, an arm connected to the stub shaft, a reverse L-shaped arm connected to the lower end of the aforesaid arm at the bottom, an adjusting device secured to the head of the door frame, a pivotal connection between the adjusting device and the upper end of the L-shaped arm, a double plate secured to the inner edge of the door, arbors journaled in the plate, meshing gears secured in the arbors, an arm secured on the lower arbor, a rod connecting the arm and lower arbor to the arm on the shaft journaled in the door, an adjusting device secured to the head of the frame, a rod connecting the arm on the lower arbor to the adjusting device, an arm on the upper arbor, a rod connected to the upper end of the arm and means for adjusting the rod vertically as and for the purpose specified.

4. In a door hanger, the combination with the door and suitable guide-ways therefor, of a stub shaft journaled in the door, an arm connected to the stub shaft, a reverse L-shaped arm connected to the lower end of the aforesaid arm at the bottom, an adjusting device secured to the head of the door frame, a pivotal connection between the adjusting device and the upper end of the L-shaped arm, a double plate secured to the inner edge of the door, arbors journaled in the plate, meshing gears secured on the arbors, an arm secured on the lower arbor, a rod connecting the arm and lower arbor to the arm on the shaft journaled in the door, an adjusting device secured to the head of the frame, a rod connecting the arm on the lower arbor to the adjusting device, an arm on the upper arbor, a rod connected to the upper end of the arm, a bar supported in brackets and pivotally connected to the depending rod and means for adjusting said

bar vertically as and for the purpose specified.

5. In a door hanger, the combination with the door and suitable guide-ways therefor, of a stub shaft journaled in the door, an arm connected to the stub shaft, a reverse L-shaped arm connected to the lower end of the aforesaid arm at the bottom, an adjusting device secured to the head of the door frame, 10 a pivotal connection between the adjusting device and the upper end of the L-shaped arm, a double plate secured to the inner edge of the door, arbors journaled in the plate, meshing gears secured on the arbors, an arm 15 secured on the lower arbor, a rod connecting the arm and lower arbor to the arm on the shaft journaled in the door, an adjusting device secured to the head of the frame, a rod connecting the arm on the lower arbor 20 to the adjusting device, an arm on the upper arbor, a rod connected to the upper end of the arm, a bar supported in brackets and pivotally connected to the depending rod, a screw rod extending through a hole on the 25 end of the bar and provided with a nut thereon underneath the bar as and for the purpose specified.

6. In a door hanger, the combination with the door and suitable guide-ways therefor, of a stub shaft journaled in the door, an arm connected to the stub shaft, a reverse L-shaped arm connected to the lower end of the aforesaid arm at the bottom, an adjusting device secured to the head of the door frame, 30 a pivotal connection between the adjusting device and the upper end of the L-shaped arm, a double plate secured to the inner edge of the door, arbors journaled in the plate, meshing gears secured on the arbors, 35 an arm secured on the lower arbor, a rod connecting the arm and lower arbor to the arm on the shaft journaled in the door, an adjusting device secured to the head of the frame, a rod connecting the arm 40 on the lower arbor to the adjusting device, an arm on the upper arbor, a rod connected to the upper end of the arm, a bar supported in brackets and pivotally connected to the depending rod, a screw rod extending 45 through a hole on the end of the bar and provided with a nut thereon underneath the bar and means for adjusting the bar longitudinally as and for the purpose specified.

7. In a door hanger, the combination with the door and suitable guide-ways therefor, of a stub shaft journaled in the door, an arm connected to the stub shaft, a reverse-L-shaped arm connected to the lower end of the aforesaid arm at the bottom, an adjusting device secured to the head of the door frame, 55 a pivotal connection between the adjusting device and the upper end of the L-shaped arm, a double plate secured to the

inner edge of the door, arbors journaled in the plate, meshing gears secured on the arbors, 60 an arm secured on the lower arbor, a rod connecting the arm and lower arbor to the arm on the shaft journaled in the door, an adjusting device secured to the head of the frame, a rod connecting the arm on the lower arbor to the adjusting device, an arm on the upper arbor, a rod connected to the upper end of the arm, a bar supported in brackets and pivotally connected to the depending rod, a screw rod extending through 65 a hole on the end of the bar and provided with a nut thereon underneath the bar, a screw spindle pivotally connected to the lower end of the bar and extending longitudinally therewith, a lug on the plate carrying the bracket on which the bar is supported and nuts on the screw spindle on each side of the lug as and for the purpose specified.

8. The combination with a door and suitable guide-ways therefor, of a stub shaft journaled in the door, an arm connected to the stub shaft, a reverse L-shaped arm connected to the lower end of the aforesaid arm at the bottom, a lever suitably fulcrumed, 85 an arm pivotally connected to the lever at one end and to the upper end of the L-shaped arm at the opposite end, a screw spindle pivotally connected to the arm attached to the lever, a bracket through which 90 such screw spindle extends and adjusting nuts on the screw spindle and a screw spindle pivotally connected to the opposite end of the lever, a bracket through which the screw spindle extends and adjusting nuts on 95 the screw spindle as and for the purpose specified.

9. The combination with a door and suitable guide-ways therefor, of a stub shaft journaled in the door, an arm connected to the stub shaft, a reverse L-shaped arm connected to the lower end of the aforesaid arm at the bottom, a lever suitably fulcrumed, 100 an arm pivotally connected to the lever at one end and to the upper end of the L-shaped arm at the opposite end, a screw spindle pivotally connected to the arm attached to the lever, a bracket through which such screw spindle extends and adjusting 105 nuts on the screw spindle and a screw spindle pivotally connected to the opposite end of the lever, a bracket through which the screw spindle extends and adjusting nuts on 110 the screw spindle as and for the purpose specified.

10. The combination with a door and suitable guide-ways therefor, of a stub shaft journaled in the door, an arm connected to the stub shaft, a reverse-L-shaped arm connected to the lower end of the aforesaid arm at the bottom, an adjusting device secured to the head of the door frame, a pivotal connection between the adjusting device and the upper end of the L-shaped arm, a double plate secured to the 115 inner edge of the door, arbors journaled in suitable bearings attached to the back edge of the door, an arm on the arbor, a rod connecting the arm on the arbor to the arm on the stub shaft journaled in the door, and a rod extending vertically upwardly from the end of the arm on the arbor, a lever journaled in suitable bearings in the head of the 120

door frame, an arm or link connecting the one end of the lever with the aforesaid vertically extending arm, a screw spindle connected to the arm, a bracket through which the screw spindle extends and adjusting nuts on the screw spindle on each side of the bracket and a screw spindle connected to the opposite end of the lever to that on which the arm or link is connected, a bracket

through which such screw spindle extends 10 and adjusting nuts on the screw spindle on each side of the bracket as and for the purpose specified.

HUGH TODD.
